UNITED STATES PATENT OFFICE.

WALTER S. LISTER, OF CLEVELAND, OHIO, ASSIGNOR TO THE NATIONAL PRINTING MACHINE COMPANY, OF CLEVELAND, OHIO, A CORPORATION OF OHIO.

TYPE SETTING AND DISTRIBUTING MACHINE.

1,105,334.

Specification of Letter Patent.

Patented July 28, 1914.

Application filed January 16, 1908. Serial No. 411,042.

To all whom it may concern:

Be it known that I, WALTER S. LISTER, a citizen of the United States, resident of Cleveland, county of Cuyahoga, and State of Ohio, have invented a new and useful Improvement in Type Setting and Distributing Machines, of which the following is a specification, the principle of the invention being herein explained and the best mode in which 10 I have contemplated applying that principle, so as to distinguish it from other inventions. The present invention, while it relates to printing machines of the kind now quite extensively employed in offices and like situations for printing in imitation of type-writing, has more particular regard to the provision of type setting and distributing means for use in connection with such machines. In what is perhaps the best known form of 20 the above class of printing machines there are combined in a unitary structure a type holding member, a printing member, said members being respectively provided with parallel open ended grooves along which the type may be shoved, and a font of type forming a permanent part of the machine and arranged to occupy such grooves and to be transferable between them from either member to the other, the type holding member 25 being movable in order properly to coöperate with the printing member when it is desired to bring selected type-rows thereon into position where such transfer may be effected. In the machine under consideration such 30 transfer of the type from one member to the other, involving as stated the movement of one member into a proper coöperative position with respect to the other, although sometimes characterized as automatic, is in effect 35 manual in its operation, the movement of the member and the subsequent transfer of the type, furthermore, being independent operations. The desirability of combining 40 these operations and particularly of effecting them through suitable key-board mechanism whereby the selective positioning of the type-holding member may be automatically effected by striking the proper key of such 45 mechanism, has been recognized before, and 50 one form of machine illustrative of this principle is shown and claimed in a pending application of William A. Twining, filed No-

vember 25, 1907, Serial No. 403,668. So far, however, as concerns the relation of the type-holding and printing members, and the direct character of the coöperation required between them preliminarily to the transfer of type, this composing and distributing machine just referred to does not differ from that of the original multigraph. In thus adapting key-board mechanism to the operation of such printing machine a difficulty, noticeable even in the simple hand-operated form of multigraph, is accentuated; namely, that by movement of the type holding member or rather rotation thereof, this member then being desirably in the form of a drum, such momentum is acquired thereby as tends to rack the machine as well as render operation of the same difficult. In the present invention these difficulties have been overcome by a general reorganization of the machine as a whole whereby as it will be seen in the sequel, not only is the objectionable momentum referred to overcome but other 70 highly advantageous results simultaneously attained.

To the accomplishment of these and related ends, said invention, then, consists of the means hereinafter fully described and so particularly pointed out in the claims.

The annexed drawings and the following description set forth in detail certain mechanism embodying the invention, such disclosed means constituting, however, but one 85 of various mechanical forms in which the principle of the invention may be used.

In said annexed drawings: Figure 1 is a plan view of a printing machine involving my improved type of distributing and composing means, a portion of the printing member, as also parts of the majority of the key-levers, being broken away to avoid confusion; Fig. 2 is a side elevation of the invention, a portion of the casing being broken away 90 in order to reveal the construction of the interior mechanism; Fig. 3 is a front elevation, a portion of the casing, as also of the printing member, being again broken away and the key-board mechanism being substantially entirely removed in order to permit 95 illustration of the parts to the rear thereof; Fig. 4 is a perspective view of the inner type case which enters into the construction

of the machine; Fig. 5 is a similar perspective view of the outer type case wherein such inner case is supported; Fig. 6 is a perspective view of the shuttle, constituting a combined composing and distributing member, and forming a prime feature of the present invention; Fig. 7 shows, in its final operative position, a detail of the mechanism for transferring type from the type-case to printing member in the composing operation; and Fig. 8 shows, in similar final operative position, a detail of the mechanism for discharging type into the type-case in the distributing operation.

15 In the machine herewith illustrated, the printing member is shown as being in the form of a drum A permanently mounted in brackets or standards b constituting a part of the general machine frame B. This drum being thus a part of the unitary structure is designed to coöperate, for the purpose of printing, with a platen, likewise embodied in the construction of the machine, but not here shown inasmuch as it constitutes no 20 part of the present invention and the arrangement thereof, as also of inking means for the drum, are both familiar features in the art of printing. It may here be further stated that it is a matter of general indifference whether such printing drum be thus incorporated in the machine structure or not, as also whether it be a rotatable drum or not, the operation of the parts constituting the invention proper being identical whatever 25 the form, or more of use, of the printing member. Such member is provided, whatever its form, with a plurality of transversely disposed, undercut grooves or channels a within which type of suitable 30 formation may be received and held by reason of their engagement therewith as will be readily understood. In the course of the rotation of the drum these type holding channels or ways a are adapted to be 35 brought successively into alignment with a type discharge point, by which term I shall designate the position of operative relationship of a groove on the printing member with the type discharge, and transferring, 40 mechanism, presently to be described. Before taking up, however, the construction of this mechanism it is convenient to consider the construction of the type case C from which type are designed to be transferred 45 to the printing member, just described, and thence received again, in the operations of composing and distributing, respectively. As has been indicated in connection with the 50 general description of the figures of the drawings, this case is made up of two parts or members, an outermost supporting member C' rigidly mounted in the machine frame B, and in effect a part thereof, and an inner vertically movable case C², held in such 55 outer case. The outer case C' is in effect a

rectangular box provided at its respective inner corners with vertically aligned guides c that receive corresponding tongues c² on the outer corners of the inner member C², or type-case proper. Such inner case will be 60 seen by reference to Fig. 4 to consist in effect of a plurality (three as illustrated) of vertically spaced trays c², each such tray being provided with a plurality of parallel type-receiving grooves, or ways c³, exactly 65 similar to those in the printing member A and adapted like the latter to slidably hold the type employed in connection with the machine. In connection with each type-groove in the respective trays c², there is 70 provided an aligned feed-rack, or bar, c⁴ disposed directly above the groove, the respective ends of each series of bars being slotted and surrounding rods c⁵ extending transversely of the end of the case, whereby such 75 bars are supported. The conformation of the slots c⁶ is such that when any rack is given an inward longitudinal movement, it will be lowered and then advanced horizontally. Springs c⁷ normally retain the racks 80 c⁴ in their outer raised positions. The effect of the movement just described is the engagement of the teeth c⁸ on the underside of the rack with a chaser c⁹, one of which is 85 slidably carried in each of the channels or 90 ways of the type case. Operation of a feed-bar is designed to effect a sufficient movement of the particular chaser engaged thereby, to advance the line of type, against 95 which the latter presses, one type space, or 100 in other words to discharge a type from the inner end of the groove. The disposition of the type thus discharged will be taken up in a subsequent paragraph.

In the normal position of the inner type-case C² in the outer supporting case C', the uppermost of the trays c² composing such case is designed to lie substantially in the same plane with the discharge point with which, as before described, the ways or grooves a of the printing member A are aligned when in 105 operative position, Figs. 2 and 3. In order to bring either of the two other trays of the case into such operative plane, the case obviously requires to be raised a corresponding amount. For the purpose of thus raising and supporting the case there is mounted laterally of the outer supporting member of the case a rock-shaft D supported in suitable brackets c¹⁰, Figs. 1 and 2. Connected with this shaft at each end is a lever arm d which extends inwardly to approximately the center of the type case, the inner ends of each lever being connected with the inner ends of two oppositely disposed levers d' mounted 110 on the inside of the case wall and bearing segmental gears d² at their outer ends that mesh with vertical racks d³ attached to the corresponding corners of the inner type-case C². Connection between levers d and 115 120 125 130

these segmental gear levers d' is had by means of pins d^4 in the ends of the former extending through slots c^{11} in the case wall. A torsional spring d^5 mounted upon the shaft D and having its opposite ends fixedly secured in a collar d^6 on such shaft and the adjacent bracket c^{10} is adapted to almost, but not quite, sustain the weight of the inner case, so that the latter will be seen to be practically balanced. A very slight force will accordingly suffice to elevate the same when such movement becomes necessary in order to render available either of the lower trays c^2 . This elevation is had by means of a lever D' extending downwardly to the side and in front of the machine frame and provided with a key d^7 , such key being adapted when depressed to raise either the lowermost or the intermediate tray onto the operative level, as desired. A spring actuated catch D^2 formed with an inwardly projecting tooth d^8 is adapted to engage either of two pins or lugs d^9 upon such lever, to retain the latter in either of the two positions just mentioned. Upon withdrawing the catch, the lever, and with it the case, return again to their normal positions in which the upper tray is on the operative level.

For the purpose of receiving a type discharged from any type-row in the manner previously described, and thereupon to carry such type into a position where it may be in turn discharged onto the printing member, an intermediate member, or shuttle E , movable transversely of the type rows of the particular tray of the type-case occupying the operative plane is provided. Such member, as will appear, is equally adapted to receive type from the printing member, carry the same to a selected type-row in such type case and there deposit the same so that the shuttle member may be properly termed a combined composer and distributor. In conjunction with this same shuttle are provided means for thus effecting the transfer thereto of type from either the type-case or the printing member and the discharge thence into the printing member or type-case, together with key-board mechanism for selectively locating the shuttle and actuating such means.

In construction the shuttle member E in the approved form illustrated consists simply of a short transversely disposed bar approximately equal in length to the width of the type-case and mounted in suitable ball-bearings b^2 in a portion of the machine frame extending up between the type case and the printing member. The upper portion of the bar is of a width just sufficient to occupy the space between the type case and printing member and is formed approximately at its center with a transverse slot e of the same cross-sectional form as the slots or grooves in the type case and print-

ing member. Such face is further provided with a flange e' that extends laterally a short distance above and over the printing drum, an aperture e^2 in the vertical portion of this flange permitting the free passage therethrough of the heads of the type, the lower portions of which are guided in the slot e aforesaid. Pivotally mounted in the bar constituting the shuttle, at a point adjacent to this slot e , is a lever E' provided with a lug e^4 adapted to engage with the inner ends of the respective feed bars mounted as before described in the type case, the character of this engagement being such that free movement of the lever transversely of the bars to locate the same in operative relation with any one of the latter is permitted. The upper end of the lever extends above and across the flange e' just described, and is resiliently drawn toward a support or standard e^5 mounted on the upper face of the shuttle, and on the opposite side of the groove e , by means of a spring e^6 .

Depression of the upper end of the lever E' , and consequent actuation of an operatively adjacent rack-bar c^4 , is designed to be effected irrespective of the position of the lever, by reason of the displacement of the shuttle, by means of a universal bar E^2 oscillatorily mounted on a transverse shaft c^3 above the path of travel of the shuttle. The ends of such shaft whereon this universal bar is thus mounted are supported in brackets b^4 rising from the general machine frame at the front and rear end of the outer fixed member C' of the type case. The effect of such actuation of the lever E' and consequent inward movement of a rack-bar is, as has already been stated in connection with the description of the latter, the transfer of one type from the adjacent type row onto the shuttle. From the shuttle, the type are then in turn discharged onto the printing drum, such final discharge being automatically effected upon the return of the shuttle to its normal position by means of a plunger e^7 that forms the upper end of an oscillatory lever E^3 mounted in the outer member of the type-case adjacent to the discharge point, Figs. 2 and 5. This plunger does not enter the groove e in the shuttle, but merely engages the upper ends or heads of the type; the plunger's movement, moreover, is merely sufficient to shove the type along for a space equal to that occupied by one type. In other words, it is designed, in the machine illustrated, that the type shall accumulate in the groove of the shuttle until such groove is full.

The effect of the shifting movement last described will thereafter obviously be the discharge of the type one by one from the side farthest removed from the plunger. A spring e^8 , Fig. 5, tends to actuate the lever and plunger; the latter, however, is held in

retracted position except when the shuttle is normally positioned by engagement of a roller e^9 borne by the lever with the lateral surface of the shuttle. A notch or depression e^{10} properly located in such surface, however, permits the forward movement of the plunger at the desired time. Whenever it becomes desirable or necessary the plunger e^7 may be held inactive, a manually operated catch e^{11} adapted to engage a notch e^{12} being provided in connection with the latter for this purpose. It will obviously be thus necessary to restrain plunger e^7 during the converse of the composing operation just described, namely that of distributing type. Such converse operation, that of distributing the type, will obviously involve a re-transfer, in the first place, of the type one by one from the groove a of the printing drum 20 alined with the discharge point, into the groove e in the shuttle, and secondly the discharge of the type from such shuttle groove into the selected groove c^3 of the type-case where the type are stored. The transfer of the type from the printing drum to the shuttle is effected in the normal position of the latter by the operation of a rack bar E^4 mounted in the same fashion of the bars c^4 previously described as being employed in connection with the type grooves in the type case. In other words, such bar E^4 is provided at its respective ends with slots e^{13} surrounding pins e^{14} carried on the frame of the machine, the conformation of the slots 30 being such that when the rack is given an inward longitudinal movement it will be lowered and then advanced horizontally. The effect of such movement as before, is the engagement of the teeth e^{15} on the under side 40 of the rack with a chaser a^3 in the groove a whereby the desired advance of the type in front of said chaser is had. A spring e^{16} normally holds the bar in its inner position, from which it will be seen that the operative 45 movement of the bar is effected by the action of such spring. In the operation of distributing type the bar is normally held retracted, with the spring in question under tension, by the engagement of a roller e^{17} on the inner end of the bar with the edge of the flange e' previously described as extending a short distance over the printing drum. At a point, however, on such flange in line with the type holding groove of the shuttle a 50 notch or recess e^{18} is cut, into which the roller e^{17} enters when the shuttle is normally positioned. By such entry the bar is permitted under actuation of the spring e^{16} to advance the type in row a one type space. 55 This movement it will be seen effects the transfer of the type from the groove in the printing drum into groove e of the shuttle whereby it may be carried, upon appropriate movement of the latter, into alinement with any selected groove c^3 of the type 60 case. As in the composing operation the type are only finally discharged from the shuttle after the groove therein has been filled and cognizance must be taken of this fact in beginning the operation of the machine. Movement of the type accumulated 70 in the shuttle to effect the discharge of the one on the side adjacent to the type-case into a groove c^3 in the latter is had by means of a dog e^{19} pivotally mounted on the lower end of an oscillatory lever E^5 that is adapted to be actuated by means of a universal bar E^6 similar and adjacent to the bar E^2 previously described as adapted to operate lever E' . A suitably disposed spring e^{23} normally retains lever E^5 in retracted position, in which position dog e^{19} is raised out of active relation to groove e by engagement of the edge of opening e^2 , such edge being preferably inclined as shown in Fig. 8. The dog 80 appears in its raised position in Fig. 2. As soon, however, as said dog is moved forwardly upon depression of lever E^5 another spring e^{24} connected with the heel of the dog throws the latter down into its active position. The bar E^6 is fixedly mounted upon the same shaft e^8 about which such other bar E^2 is oscillatory. As in the case of lever E' for transferring type from the type case to the shuttle, so operation of this lever E^5 for restoring type to the case may obviously be had irrespective of the position of the shuttle by reason of the above construction of the actuating means. A small cam-lever e^{22} holds feed bar E^4 inactive during the composing operation. This cam-lever is shown in Fig. 2 where it appears in full lines in operative position; its position when inoperative being indicated in dotted lines. When feed-bar E^4 is held inactive by cam-lever e^{22} , universal bar E^6 is likewise designed to be disconnected from its peculiar operating mechanism, or otherwise rendered inoperative as will be presently explained. 90

It has already been indicated that key-board mechanism is utilized to shift the shuttle in order to bring the groove e thereon into alinement with any selected type-row of the type-case, as also to actuate the transfer mechanism proper, such actuation, in view of the preceding description, involving operation of the two universal bars E^2 , E^6 , whereby levers E' , E^5 are respectively oscillated. This key-board mechanism is conveniently mounted in that portion of the machine frame directly beneath the holding-member C . Such mechanism comprises a plurality of levers F provided at their forward extremities with keys f of the usual construction and oscillatorily mounted upon a transverse shaft F' , that is centrally alined beneath the type-case. Parallel with shaft F' , upon which the key levers are thus mounted, and to the rear thereof is mounted a second shaft F^2 provided with a plurality 100

105

110

115

120

125

130

of segmental gears f' of which a portion project in a general forward direction, and the remainder in a general rearward direction. The rear ends of the key levers F are correspondingly formed into segmental gears f^2 adapted to mesh with such forwardly extending gears f' or else are provided with linked connections f^4 for actuating segmental gears f^6 , supported from a 10 third shaft F^3 to the rear of shaft F^2 , that are adapted to engage with the rearwardly projecting gears f' . Normally the gears f^2 of the key levers do not mesh with those f' on the shaft F^2 , their arcs being parts of 15 circles properly tangent but not themselves touching; a very slight movement of any gear f' , however, suffices to engage the corresponding gear f^2 , while the shaft is left perfectly free to rotate so far as the other 20 gears are concerned. Actuation of the key levers F will accordingly effect a rotation of the shaft F^2 , either forwardly or rearwardly, and for a predetermined amount depending upon the particular gear engaged. 25 Such various rotation of the shaft is translated into corresponding reciprocable movement of the shuttle E , either forwardly or rearwardly from its normal position, by means of a lever F^4 , borne by the inner end 30 of shaft F^2 , and a link f^8 connecting the upper end of the lever with the shuttle aforesaid.

Having once determined which tray e^2 of the inner type-case C^2 is to be employed by 35 depressing key D' the proper amount and securing it in such position, depression of the proper key lever F of the key-board mechanism just described will suffice to bring the groove e on the shuttle into operative position with respect to a predetermined type-groove e^3 of the type case as will be 40 obvious. Except when thus displaced by actuation of a key lever the shuttle is retained in its normal position by means of 45 two levers f^7 resiliently pressed against opposite sides of the lever F^4 , through which movement of shaft F^2 is transferred to the shuttle by springs f^9 . Pins f^8 serve as 50 steps to restrain undue movement of the centering levers such as might arise from an inequality in the strength of the springs. To more accurately center the shuttle in 55 such normal position than is possible by the means just described, reliance is placed upon engagement of the roller e^8 , borne by lever E^7 , with the notch e^{10} in the side of the shuttle. It will likewise obviously be also necessary to provide means for accurately 60 centering the shuttle groove e with respect to the several type grooves e^3 of the type-case. To this end the lower edge of the bar constituting the shuttle is provided with a rack 65 e^{11} having triangular, or V-shaped teeth so disposed with respect to a vertically reciprocable plunger F^6 that when the latter en-

gages any particular notch therein the groove of the shuttle will be in exact alignment with a corresponding groove or way of the type-case. The weight of such plunger F^6 , which is made up of two parts, one f^{10} 70 movable within the other f^{11} and normally held apart by means of a spring f^{12} , is sufficient normally to hold the same out of engagement with the rack; it is however, adapted to be urged upwardly to engage the 75 rack by means of a lever h connected through a link h' with a universal bar h^2 lying beneath the key-levers of the key-board mechanism above described. This bar is constructed as usual as an element of a frame 80 H , the side members h^3 of which lie within the respective sides of the machine frame and are pivotally mounted on the same shaft F' as the key levers. Such actuation of the plunger is designed to be a second operation 85 resulting from the striking of any key, but not necessarily the last, since by virtue of the construction of the plunger further movement of the universal bar will obviously be possible, such further movement being 90 utilized to actuate the type transferring or discharge means as will be presently set forth.

Transversely of the machine and adjacent to the end of shaft F^2 is a short rock 95 shaft H' , provided with a lever h^4 extending inwardly and adapted to be actuated by the universal bar just described through a linked connection h^5 . Upon the other end of such rock shaft is mounted an upwardly 100 extending arm h^6 , the upper extremity of which is bifurcated and loosely engages a clutch disk h^7 whereby connection of the shaft F^2 with the lever F^4 is controlled, the result of the actuation of the rock shaft by 105 the universal bar being to render the clutch inoperative. The time of such release and the actuation of the plunger F^6 are relatively so adjusted that the former movement occurs just after the forward tooth of the 110 notch in the rack e^{10} of the shuttle, which it is desired to have engaged by the plunger, has passed the latter; the plunger will then enter the selected notch and center the shuttle even though the latter may have 115 passed a short distance beyond its proper stopping point.

Movement of the respective universal bars E^2 , E^6 whereby the type transferring levers E' , E^5 are oscillated is derived from the universal bar H just referred to, by means of a link h^8 the upper end of which is adapted to be optionally connected with either one of such universal bars. An approved form for such variable connections is that illustrated 120 Figs. 1, 2 and 3, in which the side members of the bar frames are spaced far enough apart to permit such upper end of the connecting rod to extend between the same, the connection being had by means of engagement of one or 125

the other of two oppositely disposed headed pins h^9 on such end with properly formed slots e^{21} in the respective side members.

The operation of the machine as a whole should be fully apparent from the description of the construction of its component portions and the individual operation of the latter, and so need not be here again recounted. It may well be pointed out, however, by way of conclusion, that by the construction illustrated in the machine just described an essentially new principle of operation in devices of the class in hand is exemplified. In other words, instead of making the type-holding member coöperative with the printing member a third independent member is utilized, which member is adapted to coöperate first with such type-holding member and then with such printing member or vice versa, depending upon the character of the operation involved. The adaptation of the key-board mechanism to the actuation of a machine built on this principle, while simple, nevertheless renders possible the attainment of numerous advantages impossible in a machine of the old character. Chief among these is that arising from the fact that the movable member, here the shuttle E , may be made of very light construction, and the factor of momentum being almost entirely eliminated. Since greater speed can be introduced into the various movements of the machine and particularly of this part, as compared with that where a heavily laden type case is to be moved, no loss of time in the operation is involved by the division of the type-transfer movement into two steps.

It will of course be understood that while the shuttle member is here shown as having a simple reciprocable movement, it may also be mounted so as to be oscillatory about a fixed axis, its present movement being of course, mathematically considered, simply movement in a arc of infinite radius. The shape of the type-case trays will be modified to correspond or align with the path of movement of the shuttle, where such path is curved. By having the type-case and printing member correspond with each other in form, it is further contemplated that the printing member may be utilized in effect as the shuttle member, the type being transferred directly instead of through the intermedium of a shuttle.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. The combination with a member carry-

ing a font of type in rows, of a second member having a variable range of movement relatively to said first member and directly coöperative therewith to receive type from, or deliver type to, different rows therein in different positions of said second member respectively. 70

2. The combination of a member carrying a font of type in rows, a movable member directly coöperative therewith to receive type from, or deliver type to, different rows therein in different positions of said second member respectively, and means for limiting the movement of said second member. 75

3. The combination of a member carrying a font of type in rows, a movable member directly coöperative therewith to receive type from, or deliver type to, different rows therein in different positions of said second member respectively, and means adapted 80 to limit the movement of said second member to various predetermined distances. 85

4. The combination of a member carrying a font of type in rows, a movable member directly coöperative therewith to receive type from, or deliver type to, different rows therein in different positions of said second member respectively, and selective mechanism adapted to limit the movement of said second member to any desired distance. 90 95

5. The combination of a member adapted to carry type in rows, a second member, adapted in different positions relatively to said first member to receive type from, or deliver type to, different rows therein respectively, means for limiting the movement of said second member, and key-board mechanism adapted to impart movement to said second member and actuate said limiting means. 100 105

6. The combination of a member adapted to carry type in rows, a second member adapted in different positions relatively to said first member to receive type from said rows respectively, means for limiting the movement of said second member, key-board mechanism adapted to impart movement to said second member and actuate said limiting means, and means adapted to transfer type from any such row to said second member when the latter is positioned in operative relation thereto. 110 115

7. The combination of a member carrying a font of type in rows, a second member having a variable range of movement relatively to said first member and directly coöperative therewith to receive type from, or deliver type to, different rows therein in different positions of said second member respectively, and means adapted to discharge type from said second member to any such row when positioned in operative relation to the same. 120 125

8. The combination of a member carrying a font of type in rows, a movable member 130

- directly coöperative therewith to receive type from, or deliver type to, different rows therein in different positions of said second member respectively, means for limiting the movement of said second member, and means adapted to discharge type from said second member to any such row when positioned in operative relation to the same.
9. The combination of a member carrying a font of type in rows, a movable member directly coöperative therewith to receive type from, or deliver type to, different rows therein in different positions of said second member respectively, means adapted to limit the movement of said second member to various pre-determined distances, and means adapted to discharge type from said second member to any such row when positioned in operative relation to the same.
10. The combination of a member adapted to carry type in rows, a movable member directly coöperative therewith to deliver type to different rows therein in different positions of said second member, respectively, selective mechanism adapted to limit the movement of said second member to any desired distance, and means adapted to discharge type from said second member to any such row when positioned in operative relation to the same.
11. The combination of a member adapted to carry type in rows, a second member adapted in different positions relatively to said first member to deliver type to said rows respectively, means adapted to limit the movement of said second member to various predetermined distances, key-board mechanism adapted to impart movement to said second member and actuate said limiting means, and means adapted to discharge type from said second member to any such row when positioned in operative relation to the same.
12. The combination of a member carrying a font of type in rows, a movable member directly coöperative therewith to receive type from, or deliver type to, different rows therein in different positions of said second member respectively, and selective mechanism adapted to move said second member to a position in operative relation with any desired row on said first member.
13. The combination of a member adapted to carry type in rows, a second member adapted in different positions relatively to said first member to receive type from, or deliver type to, said rows respectively, and key-board mechanism adapted to move said second member to a position in operative relation with any selected row on said first member.
14. The combination of a member adapted to carry type in rows, a movable member directly coöperative therewith to receive type from, or deliver type to, different rows
- therein in different positions of said second member respectively, selective mechanism adapted to move said second member to a position in operative relation with any desired row on said first member, and means adapted to transfer type from any such row to said second member when the latter is thus positioned.
15. The combination of a member adapted to carry type in rows, a second member adapted in different positions relatively to said first member to receive type from, or deliver type to, said rows respectively, key-board mechanism, and means adapted to transfer type from a row on said first member to said second member when the latter is positioned in operative relation thereto, said key-board mechanism being adapted to move said second member to a position in operative relation to any desired row on said first member and thereupon to actuate said transfer means.
16. The combination of a member adapted to carry type in rows, a movable member directly coöperative therewith to deliver type to different rows therein in different positions of said second member, respectively, selective mechanism adapted to move said second member to a position in operative relation with any desired row on said first member, and means adapted to discharge type from said second member to any such row when the former is thus positioned.
17. The combination of a member adapted to carry type in rows, a second member adapted in different positions relatively to said first member to deliver type to said rows respectively, key-board mechanism, and means adapted to discharge type from said second member to a row on said first member when the former is positioned in operative relation to such row, said key-board mechanism being adapted to move said second member into such operative relation to any desired row and thereupon to actuate said discharge means.
18. The combination of a member carrying a font of type in rows, a second member adapted to receive type from, or deliver type to, said first member and movable into direct operative relation with any selected row thereon, and means tending to retain said second member in a predetermined position.
19. The combination of a member carrying a font of type in rows, a movable member directly coöperative therewith to receive type from, or deliver type to, different rows therein in different positions of said second member, respectively, means normally positioning said second member, and selective mechanism adapted to move said second member from its normal position to a position in operative relation with any desired row on said first member.

20. The combination of a member adapted to carry type in rows, a second member adapted in different positions relatively to said first member to receive type from, or deliver type to, said rows respectively, means normally positioning said second member, and key-board mechanism adapted to move said second member from its normal position to a position in operative relation with any selected row on said first member. 70
21. The combination of a member adapted to carry type in rows, a second member adapted to receive type from said first member and movable into direct operative relation with any selected row thereon, means adapted to transfer type from any such row to said second member when the latter is thus positioned, and means normally positioning said second member in alignment with a relatively fixed discharge point. 75
22. The combination of a member adapted to carry type in rows, a second member adapted to receive type from said first member and movable into direct operative relation with any selected row thereon, means normally positioning said second member in alignment with a relatively fixed discharge point, and other means adapted to discharge type therefrom when thus positioned. 80
23. The combination of a member adapted to carry type in rows, a second member adapted to receive type from said first member and movable into direct operative relation with any selected row thereon, means normally positioning said second member in alignment with a relatively fixed discharge point, means adapted to transfer type from a row on said first member to said second member when the latter is thus properly positioned in relation thereto, and other means adapted to discharge type from said second member when in its normal position. 85
24. The combination of a member adapted to carry type in rows, a second member movable relatively to said first member to receive type from any selected row thereon, means normally positioning said second member in alignment with a relatively fixed discharge point, means adapted to transfer type from any row on said first member to said second member when the latter is moved into proper relation thereto, and other means adapted automatically to discharge type from said second member upon return of the same to its normal position. 90
25. The combination of a member adapted to carry type in rows, a second member movable relatively to said first member to receive type from any selected row thereon, means normally positioning said second member in alignment with a relatively fixed discharge point, means adapted to transfer type from any row on said first member to said second member when the latter is moved into proper relation thereto, and other means adapted automatically to discharge type from said second member upon return of the same to its normal position. 95
26. The combination of a member adapted to carry type in rows, a second member adapted to deliver type to said first member and movable into direct operative relation with any selected row thereon, means adapted to discharge type from said second member to any such row when said second member is thus positioned, and means tending to retain said second member in a predetermined position. 100
27. The combination of a member adapted to carry type in rows, a second member adapted to deliver type to said first member and movable into direct operative relation with any selected row thereon, means adapted to discharge type from said second member to any such row when said second member is thus positioned, means normally retaining said second member in a predetermined position, and means adapted to feed type onto said second member when thus normally positioned. 105
28. The combination of a member adapted to carry type in rows, a second member adapted to deliver type to said first member and movable into operative relation with any selected row thereon, means adapted to discharge type from said second member to any such row when said second member is thus positioned, means normally retaining said second member in a predetermined position, and means adapted automatically to feed type onto said second member upon return of the same to its normal position. 110
29. The combination of a member adapted to carry type in rows, a second member adapted to deliver type to said first member and movable into operative relation with any selected row thereon, means adapted to discharge type from said second member to any such row when said second member is thus positioned, means normally retaining said second member in a predetermined position, means adapted automatically to feed type onto said second member upon return of the same to its normal position, and key-board mechanism adapted to move said second member into operative relation with any desired row on said first member and thereupon to actuate said discharge means. 115
30. The combination of a type case carrying a font of type in rows, a member movable transversely of the rows of said type case and directly cooperative with said type case to receive type from, or deliver type to, different rows therein at different positions of said member respectively and 120

selective mechanism adapted to move said member to a position in operative relation to any desired row on said type case.

31. The combination of a type-case adapted to carry type in rows, a member movable transversely of such rows and adapted in different positions to receive type from, or deliver type to, the same, respectively, and key-board mechanism adapted to move said member to a position in operative relation to any selected row on said type-case.

32. The combination of a type-case adapted to carry type in rows, a member movable transversely of such rows and adapted in different positions to receive such type therefrom, respectively, key-board mechanism, and means adapted to transfer type from a row on said type-case to said member when the latter is positioned in operative relation thereto, said key-board mechanism being adapted to move said member to a position in operative relation with any desired row on said type-case and thereupon to actuate said transfer means.

33. The combination of a type-supply member adapted to carry type in rows, a printing member, and a shuttle member movable relatively to said type-supply and printing members, said shuttle member being adapted in various positions to receive type from, or deliver type to, the respective rows of said type-supply member.

34. The combination of a type-supply member adapted to carry type in rows, a printing member, and a shuttle member movable relatively to said type-supply and printing members, said shuttle member being adapted in various positions to receive type from, or deliver type to, the respective rows of said type-supply member, and in one position deliver type to, or receive type from, said printing member.

35. The combination of two members adapted to carry type in rows, one of said members being a type-supply member and the other a printing member, and a shuttle member movable relatively to said type-supply and printing members, said shuttle member being adapted in various positions to receive type from, or deliver type to, the respective rows of said type-supply member, and in one position to deliver type to, or receive type from, said printing member, the latter also being movable to bring any row thereon into alignment with such last-named position of said shuttle member.

36. The combination of a type-supply member adapted to carry type in rows, a printing member, a shuttle member movable relatively to said type-supply and printing members, said shuttle member being adapted in various positions to receive type from, or deliver type to, the respective rows of said type-supply member, and in yet another position to deliver type to, or receive

type from, said printing member, and means normally retaining said shuttle member in such last-named position.

37. The combination of a type-supply member adapted to carry type in rows, a printing member, a shuttle member movable relatively to said type-supply and printing members, said shuttle member being adapted in various positions to receive type from the respective rows of said type-supply member, and in one position to deliver type to said printing member, means adapted to transfer type from a row on said type-supply member to said shuttle member when the latter is in operative relation to such row, and means adapted to transfer type to said printing member from said shuttle member when the latter is in operative relation thereto.

38. The combination of two members adapted to carry type in rows, one of said members being a type-supply member and the other a printing member, a shuttle member movable relatively to said type-supply and printing members, said shuttle member being adapted in various positions to receive type from the respective rows of said type-supply member, and in one position to deliver type to said printing member, means adapted to transfer type from a row on said type-supply member to said shuttle member when the latter is in operative relation to such row, and means adapted to transfer type to said printing member from said shuttle member when the latter is in operative relation thereto, said printing member also being movable to bring any row thereon into alignment with such last-named position of said shuttle member.

39. The combination of two members adapted to carry type in rows, one of said members being a type-supply member and the other a printing member, a shuttle member movable relatively to said type-supply and printing members, said shuttle member being adapted in various positions to receive type from the respective rows of said type-supply member, and in one position to deliver type to said printing member, means adapted to transfer type from a row on said type-supply member to said shuttle member when the latter is in operative relation to such row, means adapted to transfer type to said printing member from said shuttle member when the latter is in operative relation thereto, said printing member also being movable to bring various rows thereon into alignment with such last-named position of said shuttle member, and means normally retaining said shuttle member in such last-named position.

40. The combination of a type-supply member adapted to carry type in rows, a printing member, a shuttle member movable relatively to said type-case and printing

members, said shuttle member being adapted in various positions to deliver type to the respective rows of said type-supply member, and in one position to receive type from said printing member means adapted to transfer type from said shuttle member to a row on said type-supply member when said shuttle member is in operative relation to such row, and means adapted to transfer type from said printing member to said shuttle member when the latter is in operative relation thereto.

41. The combination of two members adapted to carry type in rows, one of said members being a type-supply member and the other a printing member, a shuttle member movable relatively to said type-supply and printing members, said shuttle member being adapted in various positions to deliver type to the respective rows of said type-supply member, and in one position to receive type from said printing member, means adapted to transfer type from said shuttle member to a row on said type-supply member when said shuttle member is in operative relation to such row, and means adapted to transfer type from said printing member to said shuttle member when the latter is in operative relation thereto, said printing member also being movable to bring any row thereon into alignment with such last-named position of said shuttle member.

42. The combination of a type-supply member adapted to carry type in rows, a printing member, a shuttle member movable relatively to said type-case and printing members, said shuttle member being adapted in various positions to deliver type to the respective row of said type-supply member, and in one position to receive type from said printing member, means adapted to transfer type from said shuttle member to a row on said type-supply member when said shuttle member is in operative relation to such row, means adapted to transfer type from said printing member to said shuttle member when the latter is in operative relation thereto, and means normally retaining said shuttle member in such last-named position.

43. The combination of two members adapted to carry type in rows, one of said members being a type-supply member and the other a printing member, a shuttle member movable transversely of the rows of said type-supply member and adapted to receive type from such rows, respectively, and means normally positioning said shuttle member in alignment with a relatively fixed discharge point, said printing member being also movable to bring successive rows thereon into alignment with such point.

44. The combination of two members adapted to carry type in rows, one of said members being a type-supply member and the other a printing member, a shuttle mem-

ber movable transversely of the rows of said type-supply member and adapted to receive type from such rows, respectively, means normally positioning said shuttle member in alignment with a relatively fixed discharge point, said printing member being also movable to bring successive rows thereon into alignment with such point, and key-board mechanism adapted to move said shuttle member from its normal position into operative relation with any desired row of said type-holding member.

45. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alignment with a relatively fixed discharge point, and means adapted to discharge type from said shuttle to said printing member when the former is thus normally positioned.

46. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alignment with a relatively fixed discharge point, means adapted automatically to discharge type from said shuttle to said printing member upon return of the former to its normal position.

47. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alignment with a relatively fixed discharge point, means adapted to transfer type from any row on said type-holding member to said shuttle member when the latter is moved into proper relation thereto, and other means adapted to discharge type from said shuttle member to said printing member when said shuttle member is in its normal position.

48. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alignment with a relatively fixed discharge point, means adapted to transfer type from any row on said type-holding member to

- said shuttle member when the latter is moved into proper relation thereto, other means adapted automatically to discharge type from said shuttle to said printing member upon return of said shuttle member to its normal position, and key-board mechanism adapted to move said shuttle member into operative relation with any desired row on said type-holding member and thereupon to actuate said transfer means.
49. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alinement with a relatively fixed discharge point, said printing member being also movable to bring successive rows thereon into alinement with such point, and means adapted to transfer type from said printing member to said shuttle when the latter is thus normally positioned.
50. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alinement with a relatively fixed discharge point, said printing member being also movable to bring successive rows thereon into alinement with such point, and means adapted automatically to transfer type from said printing member to said shuttle when the latter is thus normally positioned.
51. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alinement with a relatively fixed discharge point, said printing member being also movable to bring successive rows thereon into alinement with such point, means adapted to transfer type from said printing member to said shuttle when the latter is thus positioned, and other means adapted to discharge type from said shuttle into a selected type row of said type-holding member when said shuttle is moved into proper relation thereto.
52. The combination of two members adapted to carry type in rows, one of said members being a type-supply member and the other a printing member, a shuttle member movable transversely of the rows of said type-supply member and adapted to receive type from such rows, respectively, means normally positioning said shuttle member in alinement with a relatively fixed discharge point, said printing member being also movable to bring successive rows thereon into alinement with such point, means adapted to transfer type from said printing member to said shuttle when the latter is thus positioned, other means adapted to discharge type from said shuttle into a selected type row of said type-holding member when said shuttle is moved into proper relation thereto, and key-board mechanism adapted to move said shuttle member into operative relation with any desired row on said type-holding member and thereupon to actuate said transfer means.
53. The combination of a type case arranged in a plurality of banks, a coöperating type conveyer, means for distributing type from the conveyer to either bank, a keyboard coöperable with either bank, and a shift for determining the bank with which the keyboard is coöperating.
54. The combination of a series of parallel type-holders, a type carrier adapted to move across the ends of said typeholders from a central position in either direction to various positions and back, means for forcing type from the carrier to any of the typeholders, and a finger key for causing the said movement of the type carrier.
55. In a type distributing machine, the combination of a type case having a plurality of typeholders, a type conveyer adapted to move across the end of said case, a common typeholder on the other side of said conveyer, means for feeding type in such common typeholder toward the conveyer and into it, and means for moving the conveyer.

Signed by me, this 14th day of January, 1908.
